TUBE CLOSURE

James R. Sheehy, Orlando, Fla.

Application September 27, 1934, Serial No. 745,806

4 Claims. (Cl. 221—60)

This invention relates to new and useful improvements in automatic closures for the discharge orifice of compressible tubes utilized for vending toothpaste, cream, and like substances.

5 An object of this invention is to provide a closure device as above described, which operates automatically when pressure on the tube is released, to seal the outlet, and which will maintain its sealed position when the tube is not in use so as to prevent accidental discharge of the 10 contents thereof.

A further object of this device is to furnish an automatic closure that is so constructed that the 15 contents of the tube are kept free of the mechanism so that the probability of fouling of the same and thereby contaminating the contents is lessened.

Various other objects and advantages of the 20 invention will become apparent from the following description and reference to the accompanying drawing wherein:

Figure 1 is a fragmentary elevational view, partly in section, showing the valve in a closed position.

25 Figure 2 is a similar view showing the valve in an open position.

Figure 3 is a sectional view taken substantially on the line 3—3 of Figure 1.

Figure 4 is a sectional view taken substantially 30 on the line 4—4 of Figure 1.

Describing the invention in detail, the reference numeral 9 designates a conventional compressible tube body having the integral neck 10 which terminates in a relatively larger discharge chamber 35 11 provided with an imperforate end wall 12 and a lateral emission orifice or port 13 adjacent the closed end thereof.

Disposed within the discharge chamber is a 40 circular closure member or valve 14. A coil spring 15, anchored at one end to the end wall of the chamber, normally urges the closure member 14 downwardly and holds the same in position to seal the orifice 13.

Connected to the closure member through the 45 medium of its stem 16 is a pressure head or plate 17 slidably operating within the neck 10 and equipped with the circumferentially spaced depending lugs 18 engaging in the bore of the neck.

In operation, when the tube body is subjected 50 to pressure, the contents force the neck valve 17 upwardly and the pressure directed against this valve is communicated to the cut-off or closure member 14, through the medium of the rigid connecting bar 16. Thereby an upward 55 movement is imparted to the closure member and

the port 13 is uncovered for dispensing the contents of the tube.

When the pressure is released, the closure member and neck valve are forced downwardly to respectively close the port 13 and the neck aperture 10, by the reflex action of the coil spring 15.

The lugs 18 depending from the neck valve 17 are adapted to maintain the same in registered alignment with the neck portion when the valve has risen upwardly into the discharge chamber 11, and to furnish guide means thereto on its downward journey when the pressure is released, thus preventing fouling of the mechanism on the upper lip of the neck portion as is clearly shown 15 in Figure 2.

The usual method of uncovering the discharge orifice is to have the tube contents directly bear against the inner face of the closure valve for imparting upward motion thereto, but there is, in such devices, a tendency for the contents to squeeze between the side walls and the closure member and thus impair the efficient operation of the closure valve. In the present device this tendency is greatly lessened because the closure 20 valve is not moved upward by direct pressure from the tube contents.

The tube contents first bear against the neck valve or baffle plate 17 and as the same moves upwardly within the neck portion, the motion is communicated to the closure member so that when the contents have reached the top of the neck, the discharge port 13 is entirely uncovered and the contents are free to pass therethrough. 30 In general, the inner face of the closure member acts more in the nature of a guide means for the tube contents on their journey to the port 13 rather than a direct pressure receiving face.

From this it will be seen that in the present 35 case, the squeezing of the material between the closure valve and the side walls of the discharge chamber, and the consequent fouling of the mechanism is practically eliminated because the pressure of the contents as they reach the closure member has been lessened and the discharge orifice provides an outlet sufficient to relieve any appreciable stress directed against the closure valve.

It is to be understood that the particular embodiment of the invention disclosed herein is of an illustrative and not restrictive character and that variations and modifications may be made with respect thereto as properly fall within the 40 scope of the appended claims.

What is claimed is:

1. A collapsible container comprising a compressible body merging into a discharge chamber having a lateral dispensing orifice or port, a closure valve slidably mounted within said chamber, resilient means normally holding the valve in position to cover the port, and a pressure head connected with said valve to move the same in opposition to the resilient means to uncover the port. 5
2. A compressible tube, a neck portion terminating in a discharge chamber of relatively large diameter having a lateral dispensing port therein, a valve member slidably mounted within said chamber, resilient means normally holding the member in position to seal the dispensing port, a pressure head normally disposed within said neck and connected with the valve member to move the same in opposition to the resilient means to 10 uncover the dispensing port.
3. In combination with a compressible tube, a neck portion terminating in a relatively large discharge chamber having a lateral dispensing orifice therein, a circular closure member slidably mounted within said chamber, a coil spring normally urging the member downwardly and holding the same in position to seal the discharge orifice, a pressure head normally disposed within 15
4. A compressible dispensing tube, a neck therefor, a discharge chamber integral with the neck, and in alinement therewith, said chamber having its outer end closed and also provided with a lateral orifice intermediate its ends, a closure member for said orifice slidably mounted within said chamber, a coil spring anchored at one end to the closed end of the chamber and having its free end engaging the said member to yieldably retain the same in position to close the orifice, a pressure actuated head disposed within the neck portion and adapted to rise beyond the confines of the same into the discharge chamber and connecting with said closure member to impart upward motion thereto in opposition to the coil spring and uncover the said orifice, and circumferentially spaced depending guide lugs carried by said head for retaining the same in 20 registered alinement with the neck portion as the pressure decreases. 25
